BURNER CONSTRUCTION

Willibald Trinks, Pittsburgh, Pa., assignor to
 Eastman Kodak Company, Rochester, N. Y., a
 corporation of New Jersey

Application January 28, 1938, Serial No. 187,445

12 Claims. (Cl. 158—99)

This invention relates to a burner construction and more particularly to a gas and/or liquid fuel burner construction for use in the production of extremely high temperatures.

5 Numerous burners have been developed and a large number of different type burner constructions are in use for various domestic and industrial heating purposes. However, in the majority of instances where a conventional type of burner 10 is employed, relatively low temperature conditions are involved. In the instance of oil cracking to produce gasoline and various other components, the temperatures may be as high as 500°—600° C. for example. Certain metallurgical 15 processes require somewhat higher temperatures.

In the present day industries there are certain processes involving use of temperatures of 900° C.—1400° C. or higher. Burners of the aforementioned low temperature type of service, if employed in the latter type high temperature operations, either initially are entirely unsuited or if they function at all, after a short period of service, failure occurs. Not only is the item of frequent repairs uneconomical, but it is readily apparent that the use at high temperatures of burners which may fail, may introduce various other difficulties as well as hazards. That is, in producing high temperatures, the fuel gases employed may be comprised of hydrogen, carbon 25 monoxide, methane, butane and the like. These fuels are usually injected under some pressure. It is therefore apparent that if the burner fails, leaks, or otherwise functions irregularly, numerous difficulties may be incurred.

30 It is therefore clear that a burner construction which will withstand the drastic conditions involved in producing high temperatures such as 900° C.—1400° C. or higher has considerable industrial value. It is also apparent that if such a burner withstands the aforementioned temperatures it will also withstand lower temperatures.

In general, the production of high temperatures utilizes fuel which naturally burns with a high flame temperature. It also requires a correct ratio of air to fuel and a quick and thorough mixing. In addition, preheated air or the use of oxygen is employed. Of these requirements my novel burner readily furnishes a rich fuel and preheated air and also a quick and thorough mixing.

45 The production of these high temperatures involves the two effects, namely, the effect of high temperature of combustion and the high temperature of preheated air. The temperature effects of the high furnace temperature upon the

burner are detrimental. These effects are warping, cracking, oxidation of the burner parts due to heat generated either in the burner mouth or else radiated back from the furnace. The effects of the use of highly preheated air cause expansion of the air duct and of the burner parts, which may likewise produce warping, cracking or other destructive influence on the parts. I have developed a novel burner which may be satisfactorily employed for purposes involving extremely high temperatures, which burner is free of various defects encountered in burners previously employed.

50 This invention has for one object to provide a burner for use under conditions involving the production of extremely high temperatures. Still another object is to provide a burner, certain parts of which are of non-rigid construction. Still another object is to provide a burner that is particularly adapted to employment for supplying heat to chemical, cracking or other type processes operating at temperatures of 1100°—1500° C. or higher. Still another object is to provide a burner adapted to consume fuels containing materials such as hydrogen, carbon monoxide, 25 methane, butane or mixtures thereof. Still another object is to provide a burner wherein there is an intimate mixing of the fuel and combustion medium prior to combustion. Still another object is to provide a burner adapted to employ pre-heated fuel and combustion air. A still further object is to provide a burner adapted for producing a short flame. Other objects will appear hereinafter.

55 For a more complete understanding of my invention, reference is made to the accompanying drawing. Fig. 1 is a semi-diagrammatic side elevation view partly in section showing one form of my burner.

Fig. 2 is a semi-diagrammatic side elevation view showing an embodiment of my burner in which certain of the parts have been modified. In the aforementioned figures, certain of the parts have been shown on exaggerated scale for clarity.

45 In Fig. 1, 2 represents the wall of a furnace which, for the purposes of illustration, my burner will be considered as attached to. This furnace wall may be of usual construction and is provided with a port 3 extending therethrough for conducting the products of combustion into a 50 heating chamber (not shown). The external burner construction may be comprised of the two parts 4 and 6.

40 The burner member 4, which may be referred to as the burner tip, may be of any suitable shape.

but preferably is conical as shown (or rounded as shown in Fig. 2). The burner tip may have affixed thereto one or more lugs as indicated at 7 and 8 for attaching the burner to the furnace wall. This may be done by means of bolts shown at 9 and 11.

Positioned at another point on the burner tip's circumference is a flange or collar 12. This part may be cast integral with the burner tip or might be welded or otherwise affixed thereto. The function of this part will be set forth hereinafter.

A portion or all of the parts just described are preferably constructed of suitable heat-resisting alloy, of which a number are described in "The Book of Stainless Steel" by Thum. It is also possible to employ various non-ferrous heat-resisting alloys such as nickel molybdenum chromium, nickel tungsten chromium, and the like. In general, I prefer to employ either a ferrous or non-ferrous metal alloyed with a substantial content of chromium.

The other external part of the burner construction 6 may comprise an elbow type conduit member as shown. This member may be comprised of the external metal shell 13 which is lined with a suitable refractory material as indicated at 14. It is possible, in place of the composite construction just described, to employ a solid heat-resisting metal piece. However, the first mentioned type of construction is sufficiently heat-resistant to withstand the temperature of the highly preheated air and economical, hence, desirable. Part 6 also terminates in a collar construction 16 which is similar to part 12 already described. In the event that the internally lined composite construction is employed, an internally extending flange or shoulder as at 17 may also be present.

The parts 4 and 6 are in the nature of a conduit for conducting combustion air from 18, for example, through 19 and thence through 21 to the burner orifice 22. These parts 4 and 6 cooperate as at 23 by means of a non-rigid, overlapping flange and preferably bell and spigot construction shown. This construction may be relatively simple and comprise the inner or spigot member 24 which is embraced by the outer overlapping or bell member 26. Shoulders may be provided at 27 and 28 for restricting the movements of these parts to some extent. It is, of course, apparent that the part 24 might be the overlapping member, whereas the part 26, the inner member. Or, it is also possible to dispense with the shoulders or abutments 27 and 28 and merely provide one conduit more or less free to move within the other.

It will be observed that parts 4 and 6 are so positioned that they do not touch each other but are constructed with some space between them. That is, there is a certain amount of clearance between these parts. Preferably, this clearance will be substantially equivalent to the vertical expansion of duct 19 relative to the furnace. While my novel construction may appear to resemble an ordinary slip joint, it is not constructed for this purpose. My construction serves several purposes, as will be more apparent as the description proceeds.

Encircling the construction and preferably extending between the collars 12 and 16 are one or more heat-shielding means 29. This means may comprise a fiber such as asbestos encased in a thin metal sheet to prevent crumbling and to preserve the shape thereof. As indicated, a plurality of such members may be positioned at

this point; or if desired, a water-cooling coil 31 may supplement the action of means 29. In other words, this construction may vary somewhat, it being desirable, however, that the medium be interposed therearound in such a manner as to prevent substantial heat transmission therethrough.

Further removed from the construction and attached to collars 12 and 16, is a metal bellows or accordion-like member 32. As apparent, this member is non-rigid and therefore permits a substantial amount of movement within the burner parts, yet at the same time does not leak or otherwise present difficulties. The aforementioned parts, such as 29, are positioned within the enclosed chamber defined by the bellows 32 and the overlapping flange construction 24, 26. By means of this structure, insufficient heat is transmitted to the exterior metal parts to cause the damage thereof.

In further regard to the bellows structure 32, it will be observed that this device is air tight. The arrangement and cooperation of the above described parts serves several purposes. It allows expansion right and left and also up and down. The bellows 32 is very flexible for right and left movements and this is desirable because of the expansion in the bustle pipe. For up and down movements the bellows 32 is more restricted. However, the movement permitted in this direction is sufficient because the expansion in pipes 19 and 13 is not very great. However, varying degrees of expansion may be taken care of, depending on the length of the bellows. That is to say, if a bellows of comparatively great length between the collars 12 and 16 is employed, change of size in pipes 19 and 13 of considerable magnitude may be taken up. With the above disclosure, one skilled in the art may readily choose the proper length of bellows depending on the size of the burner, the temperatures to be involved and other such factors.

The bell and spigot construction 26 and 24 serve the purpose of keeping the radiations of the bright interior away from the asbestos ring 29. The latter also serves to some extent for keeping radiations away from other parts of the equipment.

Extending through and at least partly housed by the aforementioned conduit defined by parts 4 and 6, is another conduit 33. This conduit is for supplying fuel to the burner tip and may be comprised of a small heat-resisting metal tube. Inasmuch as this tube is of relatively small diameter as compared to the conduit encircling it, it is possible to obtain the tube constructed of heat-resisting metal. The tube may terminate as at 34 in a nozzle member for introducing the fuel into the combustion medium. The fuel conduit may be concentrically or otherwise positioned within the first described conduit, by means of supports such as the radially disposed blades or fins 36. Another portion of the tube may be attached to the equipment by means of a collar as at 31. The tube may be packed or otherwise slidably mounted in the collar and have affixed thereto a fuel line as at 38.

From the preceding it may be seen that I have provided a burner of non-rigid construction. It is apparent that when my burner is subjected to high temperatures, even though thermal distortion is induced therein, breaks or leaks do not occur, inasmuch as by virtue of my novel construction in which various parts are free to move, the expansion and contraction is taken up. It will

also be observed that by my novel construction having the bell and spigot construction as at 23, heat conductance is stopped to some extent thereby. This makes it necessary to construct only 5 the tip or a portion of the tip as at 22 and extending back to 36 of heat-resisting metal. Also, by virtue of my construction the various protruding parts such as at 8, 12 and 16 facilitate heat dissipation. Therefore, the part 6 may be 10 constructed of more or less inexpensive materials and if desired, lined with refractory material as at 14. This insulation adequately protects the metal parts from the preheated air. Other advantages of my apparatus will become more 15 apparent from the further description with respect to Fig. 2.

In Fig. 2, a portion of my burner is shown on larger scale. This figure also indicates to some extent certain ways in which the structure may 20 be modified. In Fig. 2, 52 represents the furnace wall provided with a port 53. In the apparatus shown in this figure, the burner tip 54 is constructed spherically or rounded as shown and may be made up from heat-resisting alloy, the heat-resisting alloy welded or otherwise affixed to the remainder of the tip as at 56.

The remainder of the external portion of the tip is substantially as described in Fig. 1. That is, a lug or flange may be provided as at 57 for affixing the burner to the furnace. Further lugs or collar means are provided as at 58 for supporting the bellows or accordion-like metal member 59. As readily apparent from the drawing, the bellows member may be affixed to flange 58 by 35 means of a ring 61 positioned over the edge thereof. This ring is held in position and may be securely forced against flange 58 by means of the bolts 62 and 63. It is readily apparent that while two bolts appear in the drawing, a suitable number would be spaced around the periphery of the flange for properly attaching the bellows and rendering it air tight. The interior of the tip construction as at 64, rather than being tapered as shown in Fig. 1, may be more or less uniform and 40 cylindrical as shown in Fig. 2. As in Fig. 1, the tip includes a suitable bell or spigot construction as at 66. Inasmuch as this construction is substantially the same as already disclosed with respect to Fig. 1, further description is unnecessary. 45

50 The construction is likewise encased by means of asbestos or other such non-heat conductive material 67. This material may be compacted in a metal case 68, if desired. The heat-resistance of this means may be supplemented with cooling 55 coils 69 as shown. However, such construction is optional. In most instances by providing a thick enough layer of fibrous heat-resisting material as at 67, heat transmission is suitably cut down at these movable parts.

60 The interior of the burner as in Fig. 1, is provided with a fuel inlet conduit 71. This conduit may comprise a single heat-resisting alloy or if desired, a composite structure with heat-resisting material on the exterior thereof may be employed. 65 The fuel tube may be spaced with respect to the first-mentioned conduit by means of the whirler 72. This part, which may be in the nature of a spirally arranged blade not only serves to support the fuel tube but also may impart a rotary 70 flow to the combustion medium flowing in the passageway 73 defined by the exterior wall of the fuel tube and the interior wall of the burner tip.

75 The fuel feeding tube 71 may terminate in a nozzle construction 74 having a plurality of radi-

ally positioned small openings 76 for dispersing the fuel. Inasmuch as this part is subjected to high temperature, it will be constructed from suitable heat-resisting alloy.

The functioning of my novel burner is apparent 5 to a substantial extent from the preceding description. However, for further purposes of illustration, a brief description of burners functioning will now be set forth, reference being made chiefly to Fig. 1. Air at a temperature of several 10 hundred degrees C. is forced through the bustle pipe 18 from which a portion thereof branches off through conduits 19, 21 and finally arriving at the burner tip 22. The linear flow of this combustion medium may be rendered non-linear by 15 virtue of vanes or blades 36 or the whirler 12 of Fig. 2. Simultaneously with the introduction of the combustion medium, fuel such as hydrogen, butane, methane or mixtures thereof, is introduced as at 38 through the conduit 33. Either or 20 both, the fuel and air may be in a preheated condition. In my description I will treat them as preheated.

The preheated fuel and preheated air are 25 intimately mixed as at 22 and burned, generating an extremely high temperature. While the flame may be at some point in the port 3 removed from the burner tip 22, nevertheless the burner tip becomes heated to a high temperature, hence, the desirability of constructing this part of heat-resisting alloy. However, as already indicated, by 30 virtue of my construction the transmission of heat back along the conduit is prevented to some extent by the bellows construction and associated parts. Although the various parts of the burner are at different temperatures, thereby expanding and/or contracting to different extents, due to the non-rigid construction of my burner, there is provision for sufficient movement in all directions so that leaks and breaks do not occur. 35

40 My burner as described herein, may be used in various processes. For example, the burner may be employed in processes such as described in Wulff Patents 1,880,308 and 1,880,309 and 1,843,-965, wherein high temperatures are employed. 45 This use is merely illustrative and my burners may be employed in various other types of installation. The burners function over a long period of high temperature without leaks or failure.

50 From the preceding it is apparent that the construction is susceptible of some modification. For example, either conical or rounded ends may be employed for the burner tip. The interior of the tip casting may be cylindrical or tapered. The 55 heat-resisting means may be comprised of one or more layers or may be supplemented by means other than the shielding effect of the heat-resisting band described herein. While water-cooling adjacent the heat-resisting band has been indicated, this is optional. In general, the heat-resisting band will be constructed of a degree of thickness suitable to the temperatures to be involved. Hence, I do not wish to be restricted in my invention, excepting insofar as is necessitated by the prior art and the spirit of the appended claims.

55 What I claim is:

1. A gas burner adapted for use under conditions involving the production of high temperatures comprising an external conduit member terminating in a cylindrical end, means associated therewith for attaching the member to a furnace, a second external conduit member positioned in communicative relationship with the 75

- first member by means of a bell and spigot construction, in which the internal member of the bell and spigot does not touch the external member thereof, and an accordion-like metal cylinder 5 that extends around at least a portion of the bell and spigot and with the construction forms an enclosed chamber, a heat-resisting medium positioned in the chamber and encircling the construction, another conduit member positioned at 10 least partly within the first-mentioned conduit, and blade means connected with this latter conduit for positioning the conduit with respect to the first-mentioned conduit so that an annular passageway is formed.
- 15 2. A burner adapted for use under conditions involving the production of temperatures in excess of 1000° C., which comprises an inlet conduit for fuel, a second conduit at least partially embracing the first conduit and positioned therefrom to form a passageway, the conduits terminating in conical members to form a burner orifice, blades attached to both conduits for positioning the first conduit in the second, the burner being characterized in that the second conduit comprises a plurality of parts including a bell and spigot construction, in which the internal member of the bell and spigot does not touch the external member thereof, therebetween, insulating means enveloping said construction, and the aforementioned insulating means being enveloped by a flexible bellows construction attached to each of said parts.
- 30 3. A gas burner adapted for use under conditions involving the production of high temperatures comprising an external conduit member terminating in a burner tip, means associated therewith for attaching this member to a heating chamber, a second external conduit member positioned in communicative relationship but spaced from the first member by means of a bell and spigot construction and an accordion-like metal means that with the aforementioned construction forms a chamber, a heat-resisting medium encased in a metal container positioned 35 in the chamber and encircling said construction, another conduit member for supplying fuel, positioned at least partly within the first-mentioned conduit, and means connected with this latter conduit for positioning the conduit with respect to the first-mentioned conduit so that a substantially annular air passageway is formed.
- 40 4. A burner adapted for use under conditions involving the production of temperatures in excess of 1000° C., which comprises an inlet conduit for fuel, a second conduit for supplying oxidizing medium at least partially embracing the first conduit and positioned therefrom to form a passageway, the conduits terminating in members which form a burner orifice, whirler blades 45 attached to both conduits for positioning the first conduit in the second and for imparting a rotary movement to the medium that flows through the passageway, collars attached to the second conduit for supporting at least part of a non-rigid structure comprising overlapping flanges dividing the second conduit into two spaced parts, insulating means enveloping the flanges, and the aforementioned parts associated with the flanges being further enveloped by a 50 flexible bellows construction attached to said collars.
- 55 5. A gas burner adapted for use under conditions involving the production of high temperatures comprising an external conduit member terminating in a heat-resisting alloy end, a second 55 external conduit member positioned in communicative relationship with the first member by means of an accordion-like metal means that extends completely around a portion of the members and with the members forms an enclosed chamber, at least a portion of said members being spaced apart to form a non-rigid inner joint, a heat-resisting fibrous medium positioned in the chamber and encircling the joint, another heat-resisting alloy conduit member positioned at least 60 partly within the first-mentioned conduit, and a heat-resisting whirler member connected with this latter conduit for positioning the conduit with respect to the first-mentioned conduit so that a substantially annular passageway is formed.
- 65 6. A burner adapted for use under conditions involving the production of temperatures in excess of 1000° C., which comprises a fuel conduit, a second conduit at least partially embracing the first conduit and positioned therefrom to form a passageway for preheated air, the conduits terminating in a burner orifice, means attached to the conduits for positioning the first conduit at least partly within the second, the burner being characterized in that the second conduit is of non-rigid construction comprising at least two parts, overlapping flanges at least partially separated, at the parts junction, insulating means enveloping the flanges, and the aforementioned parts associated therewith being further enveloped by a flexible bellows construction attached to said parts.
- 70 7. A gas burner adapted for use under conditions involving the production of temperatures in excess of 1000° C., which comprises an inlet conduit for fuel, a second conduit for supplying air at least partially embracing the first conduit and positioned therefrom to form a passageway, the first mentioned conduit terminating in a tip 40 having a plurality of radially disposed openings therein, blades positioned between the conduits for spacing the first conduit in the second and for imparting a non-linear movement to the air flowing through the passageway, the burner being characterized in that the second conduit is of non-rigid construction comprising at least two sections, a freely movable and at least partially spaced apart gland construction between the sections, insulating means around the gland, 45 and an air tight flexible bellows around and attached to each of said conduit sections.
- 75 8. A gas burner adapted for use under conditions involving the production of high temperatures comprising a conduit member terminating in a conical end, lugs associated therewith for attaching this member to a furnace, a collar on this member, a second conduit member having a corresponding collar positioned in communicative relationship with the first member by means 50 of a non-rigid spaced apart internal construction having shoulders and an accordion-like metal member that extends completely around a portion of the conduit members and with said construction forms a chamber, a heat-resisting medium positioned in the chamber and encircling the construction, another conduit member positioned at least partly within the first-mentioned conduit, blade members connected with this latter conduit for positioning the conduit with respect to the first-mentioned conduit 60 so that an annular passageway is formed.
- 80 9. A burner adapted for use under conditions involving the production of temperatures in excess of 1000° C., which comprises an inlet conduit 70

109

2,183,596

5-

- for fuel, a second conduit for supplying oxidizing medium at least partially embracing the first conduit, the second conduit being of non-rigid construction comprising at least two parts, 5 a bell and spigot construction between the parts in which the internal member is at least partially spaced apart from the external member, insulating means enveloping said construction, and a flexible bellows associated with the conduit parts.
- 10 10. A gas burner adapted for use under conditions involving the production of high temperatures comprising a large conduit member, a second large conduit member positioned as an extension of the first conduit member but at least 15 partially separated therefrom, and connected thereto by means of an airtight accordion-like metal member that extends around a portion of the members, a heat-resisting medium positioned beneath said metal member and encircling a portion of both conduits, and another conduit member positioned at least partly within the first-mentioned conduit.
11. A furnace construction including a burner adapted for use under conditions involving the 20 production of high temperatures, comprising a conduit member terminating in a burner orifice, said conduit member being attached to and sup-
- 25

ported to some extent by said furnace construction, another conduit member independently supported, flexibly connected to the first conduit member, said conduit members being so positioned that they are at least partially spaced 5 apart, another conduit member for fuel housed by the aforementioned members and cooperating therewith to form a passageway for oxidizing medium, and means for supplying fuel and oxidizing medium to the respective members. 10

12. A burner construction which will withstand high temperatures and is suitable for heating the interior of enclosed chambers comprising a conduit member terminating in a burner tip of heat-resisting alloy, said conduit member 15 being adapted for support adjacent said chamber, another conduit member adapted for independent support, flexibly connected to the first conduit member, said conduit members being so positioned that they are at least partially spaced 20 apart, another conduit member for fuel housed by the aforementioned members and cooperating therewith to form a passageway for oxidizing medium, and means for supplying fuel and oxidizing medium to the respective members. 25

WILLIBALD TRINKS.
